TEMPLE FOR AN EYEGLASS FRAME

Herman Goodman, New York, N.Y., assignor to Zylite Products Co., Inc., New York, N.Y., a corporation of New York

Application April 24, 1959, Serial No. 55,642

Term of patent 14 years

(Cl. D57—1)

FIG.2

FIG.1

FIG.3

FIG.4

FIG.5

Fig. 1 is a side elevational view of a right temple for an eyeglass frame, embodying my new design;
Fig. 2 is a top plan view thereof;
Fig. 3 is an enlarged fragmentary view of Fig. 1;
Fig. 4 is a section taken at line 4—4 in Fig. 3;
Fig. 5 is a section taken at line 5—5 in Fig. 3.
I claim:

The ornamental design for a temple for an eyeglass frame, substantially as shown:
